NOZZLE

Lewis G. Morris Timpson, Plainfield, N. J.

Application March 4, 1944, Serial No. 525,066

2 Claims. (Cl. 261—116)

The present invention has for an object to provide an improved nozzle for use in producing and delivering fire extinguishing foam.

Another object is to provide a nozzle suitable for production and use in very small sizes. And another object is to provide a choice of type and quality of effluent most suitable to the peculiarities of the fire at a given moment.

The nature and object of the invention will be better understood from a description of a particular illustrative embodiment thereof for the purposes of which description reference should be had to the accompanying drawing forming a part hereof and in which

Figure 1 is a central sectional view of a foam-forming nozzle embodying the principles of the invention.

Fig. 2 is a plan view of the same.

Fig. 3 is a sectional view taken on the line 3—3 of Fig. 1.

Fig. 4 is a longitudinal section of another form of nozzle and

Fig. 5 is a sectional view taken on the line 5—5 of Fig. 4.

The basic elements of these nozzles are taken from the old art of aspiration nozzles and in particular from nozzles of the type wherein large volumes of gases are educted by small volumes of liquid under high pressure. These foam nozzles shown for the purposes of illustration provide for thorough incorporation of the gas within the liquid mass and provide adequate means to recover some of the kinetic energy of the supply stream in the form of pressure energy.

The nozzle 5 as shown in Figs. 1, 2 and 3 is designed to receive foam-forming liquid under pressure and to cause aspiration of the liquid to provide air foam and to project that foam with suitable force. As shown, the rear or base portion 6 is formed for connection to a liquid supply hose 7 and the forward tapered convergent nozzle portion or collector element 8 forming an aspirating chamber 9 is also so formed that it can be connected to a delivery hose if desired.

The aspirating chamber of the nozzle is designed to receive foam-forming liquid entering as a spray under pressure and to allow aspiration of the atmospheric air and consolidation of the two fluids. The design is such as to recover suitable pressure to project the resulting foam to the required distance and in the required quality.

Between the inlet of the nozzle and the aspirating chamber 9 a spray-forming arrangement is provided having two angularly related passages 10—10 meeting at an angle of about 60 degrees to

effect a vigorous impingement of two liquid streams upon each other. In front of the point of impingement a cylindrical baffle member or spray straightener 11 is provided which serves to confine the spray and to break up larger drops or streams and thereby greatly increase the surface area of the liquid to achieve a high volumetric aspiration of the gas. The stream of spray passing forward is well adapted for aspiration by air entering a series of holes 12 in the side of the nozzle. In order that the spray shall not exit through the holes 12 they are so positioned that all drops driving forward from the point of impingement of the two streams in the passages 10—10 which do not impinge against the baffle will pass beyond the air inlet holes before striking the wall of the nozzle.

The size of the passages 10—10 is suitably proportioned for the size of the nozzle and the rate of flow of the liquid. The present invention compensates to a large extent for such defects of manufacture in the smaller sizes as burrs, rounded edges and the like and for imperfections incident to usage such as corrosion and adherence of small particles by the provision of the protective baffle 11 interposed between the point of formation of the spray-like jet and the point of aspiration in the chamber 9. The baffle will reform elements of the spray which by faults of the nozzle have motion other than substantially forward.

Nozzles of smaller sizes can be used satisfactorily with double acting hand pumps. These nozzles do not give a constant pressure supply and the design of the nozzle may be varied to provide the best aspirating efficiency for a particular pump and the pressure available.

The ratio of contraction of the collector portion of the nozzle is about 4 to 1. The base or handle 6 has a forward protective ring 15 spaced outward from the body of the nozzle and extending far enough forward with relation to the air inlet holes 12 to prevent the holes from being accidentally closed by the hand of one using the nozzle and yet the holes freely admit air.

Variation in operation of the nozzle is afforded by the arrangement shown in Fig. 1 in that the impingement spray-forming passages 10—10 are carried in a rotatable valve member 16 which also has a passage 17 straight through at a right angle to the plane of the impingement passages 10—10. The valve member can be rotated for use to provide either a foam-producing nozzle or to provide a nozzle throwing a substantially solid stream. The effluent of the solid stream will still

cause aspiration to a certain extent and will therefore have some foam-like quality with corresponding fire-extinguishing value, and in addition the stream will have the oil-wetting power of the chemicals generally used in foam production. It will have a distance throw substantially equal to that of the usual water stream.

In many instances in the attack upon a serious oil or gasoline fire this choice of effluent will have great value. Many of these fires are of such extreme intensity that approach to them sufficiently close to apply conventional foam is impossible but the use of the substantially straight jet makes it possible to subdue the fire to such a degree that later approach for the final smothering operation will be quite feasible. At other fires splashes of some violence of a foam-like effluent are desirable to reach around walls until such subduing of the fire as will allow the conventional foam to be applied. These features of combat have particular value on ships and in crowded structures.

The nozzle shown in Figs. 4 and 5 is similar in principle to that described above.

The handle or base member 20 is formed for convenient attachment to a small hose 21. The base is threaded to receive the collector element 22 between the end of which and a shoulder of the base member a combined spray-forming element and baffle member 23 is secured. A rubber washer 24 insures a liquid-tight joint. As in the embodiment of Fig. 1 the base member is formed with a protective ring 25 which projects over the air inlet holes 26.

The preferred foam-forming liquid contains in aqueous solution as its principal active ingredient approximately 1% of sulfonated lauryl alcohol. Various other water soluble salts and esters of the saturated fatty alcohols and esters having

eight or more carbon atoms, and various solubilized proteins are also suitable. A solvent may be demanded by the conditions of service.

It will be understood that the foregoing description of particular embodiments is illustrative merely and is not intended to be construed as defining the limits of the invention. Various modifications and adaptations may be made without departing from the spirit of the invention as defined in the appended claims.

I claim:

1. A foam-forming nozzle of the character described having a plurality of forwardly directed jet-forming passages entering the rear of the nozzle at an angle to one another so as to bring a plurality of entering liquid jets into the nozzle in impinging relation one to another to form spray, lateral ports in the side of the nozzle relatively close to the position of entrance of the jets, a rotatable transverse valve member through which the jet-forming passages pass whereby rotation of the valve member will vary the spray formed, and a cylindrical baffle within which the spray is formed and by which it is confined.

2. A foam-forming nozzle of the character described having a plurality of forwardly directed jet-forming passages entering the nozzle at the rear at an angle to one another to bring a plurality of entering liquid jets into the nozzle in impinging relation to form a fine spray, a cylindrical baffle surrounding the position of impingement and extending forwardly to confine and direct the spray, and lateral ports in the exterior nozzle wall outside of the baffle for admitting air to the spray but so positioned relative to the baffle as to be protected from the spray formed within the baffle substantially as and for the purpose described.

LEWIS G. MORRIS TIMPSON.
